(57) **CLAIM**

The ornamental design for a glassware storage, as shown and described.

DESCRIPTION

FIG. 1 is a perspective view of a glassware storage showing my new design;

FIG. 2 is a perspective view thereof showing the door in an open position;

FIG. 3 is a front elevation view thereof; and,

FIG. 4 is a right side elevation view thereof.

The broken line showing in FIGS. 1-4 is included for the purpose of illustrating environment and forms no part of the claimed design.
